INVENTOR.

BY David E. Lain,

ATTORNEY.

UNITED STATES PATENT OFFICE

JESUS G. HERNANDEZ, OF SEATTLE, WASHINGTON

PORTABLE LAVATORY

Application filed July 8, 1929. Serial No. 376,596.

My invention relates to improvements in portable lavatories, and has for an object to provide a wash stand equipped with receptacles for the necessary toilet accessories which easily may be folded into a portable package and as easily unfolded and set up for use.

I attain this and other objects of my improvement with the device illustrated in the accompanying sheet of drawings in which Figure 1 is an isometric perspective front elevation of my lavatory set up ready for use and Fig. 2 is an isometric perspective of the lavatory folded in package form.

Similar characters refer to similar parts throughout. Certain parts are broken away to show other parts hidden thereby.

With more particular reference to the designated parts: A rectangular stand-top frame 20 consists of side boards 3 and top $\alpha 3$ and is supported on four legs 4, 6 preferably of angle bars the upper ends of which are fastened to side boards 3 by screws 7 extended through holes in the corners of frame 3 and engaged in registering tapped holes in legs 4.

Each of said legs consists of upper part 4 and lower part 6 overlapping and fastened to one of the corners of leg frame 5 by a screw $\alpha 7$ extended through registering holes 30 in leg parts 4 and 6 and engaged in a tapped hole in one corner of said leg frame. By preference a cross section of the members of leg frame 5 is angle-bar shape.

In an opening in stand top $\alpha 3$ flanged wash-bowl 3 is mounted. Thus the wash stand proper consists of top $\alpha 3$, side-board frame 3, spliced legs 4, 6; 4, 6; 4, 6; 4, 6, and leg frame 5, fastened together with screws 7, $\alpha 7$.

Back board 9 is hinged at its lower edge to the rear edge of the stand top with hinge 10 which allows the back board freedom to swing forward to overlie the stand top but stops movement on said hinge backward from a position at right angles to the stand top. An extension of each side edge of the back board at $\alpha 9$ is disposed at right angles thereto and forward thereof.

Two back-board leaves 11, 11 are each provided with an extension of the inner edge thereof forward at right angles to the leaf

at $\alpha 11$. The forward edges of each pair of extensions $\alpha 9$, $\alpha 11$ are hinged at 12 to allow each of leaves 11 to swing to a position forward of the back board and offset therefrom.

To the edge of each side of the stand top 55 is hinged one of top leaves 13 at hinge joint 14 adapted to allow said leaf to turn over to lie on top of the stand but not to permit it to swing downward out of parallelism with the stand top. The front end 15 of each of leaves 13 is bent at right angles thereto to stand vertically upward when the leaf is parallel with the stand top. Each rear end $\alpha 15$ of leaves 13 is like end 15, similarly disposed and parallel therewith. The outer ends of each pair of leaf ends 15, $\alpha 15$ have aligned holes therethrough the hole in end $\alpha 15$ being tapped. Towel rods 16, 16 have threaded ends $\alpha 16$, $\alpha 16$, and one of said rods is extended through said holes in each of said 60 pairs of leaf ends 15, $\alpha 15$ and the threaded end thereof is engaged in the tapped hole in leaf end $\alpha 15$.

The upper wire of the rear wall of soap holder 17 is engaged in hinge eyes 18 in back board 9. This holder is free to turn upward in said eyes. Lug $\alpha 17$ projects rearward from a lower rear corner of the soap holder to bear on the flanged rear edge of wash bowl 8. When in its illustrated position lug $\alpha 17$ 75 prevents back board 9 from swinging forward on hinge 10. Yet the construction permits of holder 17 swinging forward and upward on eyes 18 and when it is in this oscillated position the back board is free to swing forward 80 on its hinge.

Mirror 19 is fastened to back board 9. Toilet-article pockets 20, 20 are fastened to the front surfaces of leaves 11, 11. Drinking glass pockets 21, 21 are also fastened to said 85 leaves 11. Pockets 22 and 23 are also fastened to said leaves.

When set up for use the stand provides suitable accommodation for lavatory purposes as shown in Fig. 1.

When desired the stand may be packed in smaller compass as shown in Fig. 2. This is attained in the following manner: Screws 7, $\alpha 7$ are all removed, releasing the eight leg parts 4, 6 and leg frame 5 from the stand top. 100

Leaves 11 are folded over in the direction indicated by the adjacent curved arrows to stand in front of back board 9 from which they are offset by the right-angle extensions 5 *a11, a11 and a9, a9* providing room therebetween for pockets 20, 21, 22 and 23 and the toilet accessories therein. Soap holder 17 is swung upward on eyes 18 to disengage lug 17 from the flange of bowl 8 when the back 10 board with its folded-in leaves may be turned down forward to overlie the stand top *a3* and said bowl while soap holder 17 occupies a place in the bowl adjacent its rear wall. Towel rods 16, 16 are then removed from 15 arms 15, *a16* by unscrewing them from arms *a16* and withdrawing them from arms 15 when top leaves 13 are turned over to lie on top of back board 9 and arms 15, *a15* to lie alongside of the endboards 3 of the stand 20 frame with the ends of said arms projecting beyond the bottom edges of said boards 3 as shown in the packed form in Fig. 2 where said stand frame is inverted showing the bottom of bowl 8 as uppermost. The eight 25 leg parts are then packed around the edges of the bowl and leg frame 5 is stowed on top of them as shown in Fig. 2. Towel rods 16 are then replaced in operative position in arms 15, *a15* and, by construction they are 30 closely adjacent the edges of stand frame 3 and the upper web of leg frame 5, thus holding the folded and stowed parts of the lavatory in closely associated packed relation. Thus is made a package conveniently port- 35 able.

Having thus disclosed my invention, what I claim as new therein and desire to secure by Letters Patent is,—

In a portable lavatory, the combination of 40 a wash-stand top frame, a wash-stand top fastened to said top frame having an opening therethrough, a leg frame, four separably spliced legs removably fastenable to said top frame, and to said leg frame, a wash bowl 45 mounted in said opening in said stand top, a back board hinged at its bottom edge to the rear edge of said stand top oscillatable only between a position at right angles with the plane of said stand top to a position overlying 50 the same, back-board leaves joined to each side edge of said back board by forwardly offset hinges for oscillation only from a position in the plane of said backboard to a position in front of, parallel with and offset from 55 said back board, toilet-accessories holder fastened to said back board and to said back board leaves, releasable means to retain said backboard in a position at right angles to said stand top, leaves connected with hinges to 60 each side edge of said stand top for oscillation only from a position in the plane of said stand top to a position overlying the same, arms having aligned holes therethrough fastened to each end of each of said stand-top 65 leaves projected at right angles therefrom

disposed to lie alongside of the front and rear of said stand top frame when said stand top leaves overlie said stand top with their ends projected below the lower edge of said stand-top frame, and rods extended through said aligned holes in said arms engageable therewith disposed adjacent the lower edges of said stand-top frame when said stand-top leaves overlie said stand top.
